UNITED STATES PATENT OFFICE.

MAX P. HERMANN, OF PHILADELPHIA, PENNSYLVANIA.

POCKET IMPLEMENT.

1,083,095.

Specification of Letters Patent.

Patented Dec. 30, 1913.

Application filed May 16, 1910. Serial No. 561,534.

To all whom it may concern:

Be it known that I, MAX P. HERMANN, a citizen of the United States, residing in the city and county of Philadelphia, in the State of Pennsylvania, have invented certain new and useful Improvements in Pocket Implements, of which the following is a specification.

My invention relates generally, although not restrictively, to pocket knives, and to that type of implement in which the blade moves lengthwise alternately into open and closed position through the end of the handle.

15 It is the object of my invention to provide a knife or implement which shall be very simple in construction and efficient in operation, and in which the blade when in its outermost or open position, shall be rigidly held against play or lost motion in its support.

20 In the drawings I illustrate and herein I describe, a good form of a convenient embodiment of my invention, the particular subject matter claimed as novel being hereinafter definitely specified.

25 In the accompanying drawings, Figure 1 is a view in side elevation of my improved knife with the blade in closed position. Fig. 30 2 is a view of the same, looking toward the inner end, as I term it, of the device. Fig. 3 is a view in side elevation of the knife, the side wall nearest the eye being supposed removed, the block 6 however, being shown as 35 in position, notwithstanding the removal of the wall which supports it, and the blade being shown as in its intermediate position in the course of its descent to open position. Fig. 4 is a view similar to Fig. 3, the blade, 40 however, being in its outermost position, and locked in place by the controller. Fig. 5 is a view of the device, with the blade extended, sight being taken toward the upper or back edge of the handle. Fig. 6 is a view of the 45 structure, sight being taken toward the front end, with the blade in extended or open position. Fig. 7 is a view taken toward the front end of the structure, with the blade in section on the line 7—7 of Fig. 4. Fig. 8 is a 50 view, in perspective, of the controller.

Similar letters of reference indicate corresponding parts.

In the drawings, 1 is the body of the handle, of U-shape in transverse section 55 throughout its length, except at the front end portion where it is closed on all four

sides. The two side walls are designated 2, 3, respectively, the bottom wall 4, and the short top wall at the front of the structure, 5.

Conveniently the handle may be bent up 60 from a single blank of sheet metal, with the two abutting edges of the latter adjacent to the front end of the handle secured by rivets to the flat stationary metal wedge block 6, within the bore or blade chamber of the 65 handle, as shown in Fig. 1, by which arrangement the adjacent parts of the handle are retained in the desired form and set, and the said block itself retained in its desired relationship with respect to the body of the 70 handle and operative parts. The block 6 is in contact with the top wall 5, its outer edge is flush with the open mouth of the handle, and its lower edge is shaped to constitute the extended inclined plane bearing edge or 75 shoulder, 7, which as shown faces, so to speak, the inner end or interior of the handle. Said bearing edge 7 as viewed in profile as in Figs. 3 and 4, extends diagonally with respect to the wall 2 which carries it. The 80 side face of said block, which confronts or overlies the blade, is flat.

The blade 8 (or other tool) is of such size as to lie snugly within the bore or blade chamber of the handle. Said blade has at its 85 haft or base, 9, and on that side of the haft which faces the block 6, a boss 10, which latter, although I have shown it as secured by rivets to the haft, may of course be otherwise provided and may be considered as a 90 part of the haft and tool. The bottom portions of the haft and boss constitute what I term a foot 11 which projects beyond the cutting edge of the blade, and embodies or constitutes an extended plane bearing face in 95 parallelism with the handle and which rests, and in the movement of the blade slides, upon the inner face of the bottom wall 4 of the handle, with the result that the cutting edge of the said blade, whether the blade is 100 within the handle or in transit to its inner or its outer position, is assisted by said foot in being maintained out of contact with the handle, and dulling of said cutting edge which would result from constant contact of 105 said edge and handle, is diminished or avoided.

The boss 10 is conveniently, similar to the block 6, of thickness about equal to half the distance between the opposing inner faces of 110 the walls 2, 3—the side face of said boss, which opposes and is in contact with the

wall 2, is flat, and one edge is shaped to constitute the extended inclined plane bearing edge or shoulder, 13. The inner or rear end of the boss is, as shown, inclined rearwardly from its upper to its lower edge, said inner end edge constituting the inclined plane bearing edge 14.

The handle is provided with a rocking controller, 15, pivotally mounted upon the 10 walls 2, 3, and of breadth sufficient to cover or close the space between the upper edges of the said walls. Said controller is conveniently provided with an apertured head 16 for the reception of a pivot, and said 15 head contains a notch or seat 17 for the reception of a spring 18. A flange 19 which forms part of the controller, extends down between the walls 2, 3, adjacent to the wall 2. The front end of said flange, above the 20 finger 21, is positioned in a small guide recess 12 in the inner end of the top wall 5—as shown in Figs. 4 and 5—whereby said controller is guided and prevented from sidewise movement in its inward and outward movement. Said controller is conveniently formed with the tooth 20, near its rear or pivot end, the finger 21 at its front end, and the operating projection 22 at its front end.

30 The spring 18 is shown, see Figs. 2, 3, and 4, as of the form of a cross, one end projects through a small opening in the bottom wall 4, its two side arms are engaged in slight notches or seats in the end edges of the walls 35 2, 3, and its long end or arm projects within the notch 17 in the controller. The tendency of said spring is to press against the rear wall of said notch 17 and throw the front end of the controller inwardly between the 40 side walls 2, 3, that is into the position shown in Fig. 4. When the blade has passed to its outermost position, and the controller, under stress of its spring 18, has returned to its innermost or normal position, shown in 45 Fig. 4, the free end of the controller, that is to say the finger 21 in the described construction, will abut against the edge 14 at the inner or rear end of the boss, and thus prevent the rearward movement of the 50 blade, until the controller is manually elevated out of its way and into the position shown in Fig. 3.

The rear edge of the boss having the inclined bearing edge 14 as described, it is 55 obvious that in the inward or downward movement of the controller to the position shown in Fig. 4, when the blade or other tool is out or extended,—the finger 21 at the end of the controller will come to rest in a 60 position of direct contact with said edge 14, thus locking the wedge-like boss 10 into the wedge shaped space between the block 6 and the wall 4 of the handle, with the inclined or diagonal face or shoulder 13 in contact with 65 the inclined or diagonal face 7, and as a re-

sult of this arrangement, a firm locking of the tool in extended position is secured and endwise play of the tool precluded.

When the blade is in its innermost position, the tooth 20 of the controller, when the latter is in closed position, is seated, in the construction illustrated, in a recess 23 in the back of the blade, to retain said blade in such position. The finger 21 of the controller, extends beneath the inner edge of the wall 5, so that said wall will be encountered by said finger in the outward pivotal movement of the controller, hence said wall limits such outward pivotal movement and prevents the controller from being swung so far outward as to occasion misadjustment of the spring 18.

The bottom edge of the haft with its boss, as stated, rests, when the blade is in open or extended position, against the bottom wall of the handle, and the seat or region of contact extends from the lip of the handle for a considerable distance rearwardly;—a plane side face of the haft is in contact with the plane inner side face of the wall 3 of the handle, and the seat or region of contact extends from the lip of the handle for a considerable distance rearwardly;—the plane upper edge of the haft is in contact with the plane inner face of the top wall, and the seat or region of contact extends from the lip of the handle for a considerable distance rearwardly; the remaining side face of the haft, as to that portion not covered by the boss, 10, is in contact with the side face of the wedge block 6, the seat or region of contact extending the full length of said block; while the side face of the boss is in contact with the plane inner face of the wall 2, the seat or region of contact extending the full length of said boss, and the extended inclined plane bearing edge or shoulder 7 of the block is in contact with the extended inclined plane bearing edge or shoulder 13 of the boss.

By means of the arrangement just described the blade or other tool when extended is so securely encompassed in the region of its haft, by the handle, that the lateral play of the blade or tool, in use, is precluded.

The operating projection 22 projects laterally slightly beyond the wall 3 of the handle, and by it the controller may be readily swung on its pivot outwardly, to the position shown in Fig. 3, to allow the travel of the blade. To open the knife, it is held with its front or open end downward, whereupon the manual swinging of the controller outward, as shown in Fig. 3, withdraws the tooth 20 from the notch 23, and thus frees the blade, whereupon the latter will descend by gravity into the position shown in Fig. 4, and the controller, when no longer held out by the user, automatically seats itself with

its finger 21 abutting against the boss 10 to hold the blade in its extended or open position. To close the knife, it is held with its front or open end upward, and, the controller being manually swung outward, to carry its finger 21 out of the path of the blade, the latter will descend by gravity to its closed position, and the controller, when released, will, under the influence of its 10 spring, resume its closed position, and the tooth 20 will reengage in the notch 23 to retain the blade within the handle.

As will be readily understood, the arrangement of the extended inclined or diagonally disposed bearing edges or shoulders across the flat side face of the haft and the side wall of the handle, respectively, providing a wedge-like seat for a wedge-like member, greatly economizes space, and enables the structure to be made in very compact form.

Having thus described my invention, I claim and desire to secure by Letters Patent:

1. In a pocket implement, in combination, 25 a hollow handle having an open outer end, and having also an inclined surface within its outer end portion, which inclined surface faces the rear end of said handle, a tool which slides endwise with respect to said handle, and the inner end portion of which tool has an inclined surface which faces the open end of said handle and when the tool is in outermost position makes close contact with the inclined surface first mentioned, 30 and a spring controlled locking device, which when the tool is in the last described position, secures said tool temporarily in such position.

2. In a pocket implement, in combination, 40 a hollow handle having an open outer end and having also an inclined surface within its outer end portion, which inclined surface faces the rear end of said handle, a tool mounted within and which slides endwise with respect to said handle, and the inner end portion of which tool has an inclined surface which faces the open end of said handle, and when the tool is in outermost position, makes close contact with the inclined surface first mentioned, the inner 45 end portion of which tool has also a rearwardly facing inclined surface, and a controller, pivotally mounted in said handle, which controller, when the tool is in the outer position described, is free to abut against said rearwardly facing inclined surface of the tool to lock said tool against rearward movement.

3. In a pocket implement, in combination, 50 a hollow handle having a containing chamber, the outer end portion of which chamber embodies a recess of tapered character, a tool adapted to slide by gravity in either direction through said chamber and the rear 55 end portion of which tool embodies a portion

conformed to said recess and adapted when said tool is in its outermost position to enter and be wedged within said recess, to lock said extended tool tightly against lateral movement with respect to said handle, said 70 tool having a face at its rear end, a controller mounted on said handle and having movement into and out of the path of movement of said tool, and which controller when the tool is in its outermost position, is free to abut against said face at the rear end of the tool to lock said tool firmly in its wedged engagement in the outer end portion of the handle, a part of the free end of said controller extending and remaining beneath the edge of one wall of the handle, whereby the outward movement of said controller is limited, and a spring which operates to hold said controller temporarily in its innermost position.

4. In a pocket implement, in combination, a hollow handle having an open outer end, a projection rising from the surface of the interior face of said handle, and constituting a rearwardly facing shoulder arranged diagonally of the handle face which carries it, a tool mounted within and free to slide endwise with respect to said handle, a projection on the side of the inner end portion of said tool, constituting an outwardly facing shoulder extending diagonally with respect to the face of the tool portion on which it is mounted, said last mentioned shoulder making close contact with the first mentioned shoulder when the tool is in outermost position, and spring-controlled means for locking the tool in outermost position.

5. In a pocket implement, in combination, a hollow handle having an open outer end, a projection rising from the surface of the interior face of said handle and constituting a rearwardly facing shoulder arranged diagonally of the handle face which carries it, a tool mounted within and free to slide endwise with respect to said handle, a projection on the side of the inner end portion of said tool, constituting an outwardly facing shoulder extending diagonally of the face of the tool portion on which it is mounted, said last mentioned shoulder making contact with the first mentioned shoulder when the tool is in the outermost position, said tool having at its inner end a rearwardly facing inclined face, a controller pivotally mounted in the handle and having an end arranged to engage against the rearwardly facing inclined face of said tool when the tool is in outermost position, to secure said tool in such position.

6. In a pocket implement, in combination, 125 a hollow handle having an open outer end, a projection rising from the surface of the interior face of said handle and constituting a rearwardly facing shoulder arranged diagonally of the handle face which carries it,

a tool mounted within and free to slide end-
wise with respect to said handle, a projection
on the side of the inner end portion of said
tool, constituting an outwardly facing shoul-
5 der extending diagonally of the face of the
tool portion on which it is mounted, said
last mentioned shoulder making contact with
the first mentioned shoulder when the tool is
in the outermost position, said tool having at
10 its inner end a rearwardly facing contact
face, a controller pivotally mounted in the
handle and having an end arranged to en-
gage against said last mentioned face when
the tool is in outermost position, and a later-
15 ally extending operating projection carried
by said controller.

7. In combination with a knife handle, a
blade disposed therein and free for longitudi-
nal movement with respect to said handle, said
20 blade embodying a notch, said handle having
an open outer end the inner face of which
end has on each of its four sides a longitudi-
nally extending plane bearing surface, said
blade having a rear end portion or haft of
25 section corresponding to the shape of the
opening in the end of the handle, which portion
has on each of its sides a longitudinally
extending plane bearing surface which when
the blade is in its outermost position makes
30 extended contact with one of the plane sur-
faces first mentioned, said handle having on
the inner face of one of its side walls an
abruptly projecting shoulder facing the
inner end of the handle, and extending di-
35 agonally with respect to said wall, and said
haft having on its side an abruptly project-
ing shoulder facing the outer end of said
handle and extending diagonally with re-
spect to the side face of the said haft, the di-
40 agonally extending shoulder of said haft be-
ing when the haft is in its outermost posi-

tion, in close contact with the diagonally ex-
tending face of the shoulder carried by the
haft having also an inwardly
facing edge arranged to be encountered by
45 the controller, a controller pivotally mount-
ed on said handle, and movable into and out
of the path of travel of the blade, a spring
which normally maintains said controller in
a selected position, and a tooth carried by said
50 controller and adapted to engage in the notch
in the blade when the blade is in its inner-
most position.

8. In combination, a hollow handle hav-
ing an open end, a blade mounted in said
55 handle and free for longitudinal movement
with respect thereto, a controller mounted on
said handle by a pivot, a spring mounted in
the handle and operating against the con-
troller to throw the latter to a predetermined
60 set, a block or plate on the inner side wall of
said handle, that edge of the block or plate
which faces the rear end of the handle being
diagonally disposed with respect to the han-
dle, a boss formed on the blade and project-
65 ing from its side, that edge of said boss
which faces the front end of the handle be-
ing diagonally disposed with respect to the
blade, the diagonally disposed edges of the
respective block and boss being in close con-
70 tact when the blade is in its outermost posi-
tion, and said controller, when the blade is
in the last mentioned position, being in con-
tact with the rear end of the said blade.

In testimony that I claim the foregoing as
75 my invention, I have hereunto signed my
name this 28th day of April, A. D. 1910.

MAX P. HERMANN.

In the presence of—

PAUL M. HERMANN,
WM. CLEMENT LEES.
